STOCK FLOW

Edward D. Beachler, Beloit, Wis., assignor to Beloit Iron Works, a corporation of Wisconsin

Application July 18, 1952, Serial No. 299,692

11 Claims. (Cl. 92—44)

The present invention relates to a stock flow method and apparatus, and more particularly, to such method and apparatus wherein optimum flow control conditions are obtained at high speed operation and wherein the harmful effects of entrained or entrapped air in the stock are minimized.

Although it was recognized in the art that very substantial amounts of entrapped or entrained air in the stock tended to produce irregularities and defects in the paper web, it has been generally understood in the art that the problem of entrapped air was fairly well taken care of if the presence of entrapped air in the stock in the head box did not appear to be quite noticeable. The instant invention is based to a substantial extent upon the discovery that so-called hidden or small amounts of entrained air in the stock are responsible for numerous other operational difficulties in paper machines.

For example, in the usual paper machine design, the head box may have a capacity of perhaps 10% of the fan pump delivery in gallons per minute. Accordingly, relatively minor fluctuations in the fan pump delivery are reflected in the head box in the form of relatively large fluctuations in the stock level. This phenomenon was more or less accepted in the paper industry as a necessary evil resulting from the economic compact design of the head box coupled with what was believed to be unavoidably small fluctuations in the fan pump delivery rate. These fluctuations in the head box stock level have now been found by me to be reflected quite clearly in the form of variations in the texture and other physical properties of the web deposited on the forming wire.

After long and elaborate studies of numerous paper machines, I have found that irregularities in the paper web may be traced to fluctuations in the head box level during operation, which were heretofore thought to be insignificant in extent. Paper webs of extremely superior uniformity may be obtained by the use of a fixed, constantly maintained, head box stock level wherein substantially less than the previously permitted fluctuations are maintained. In fact, I have found that it is possible to select and maintain a predetermined stock level in a head box, which level is within the range of fluctuating levels heretofore maintained during operation of such head box, so as to obtain paper webs of substantially superior properties, far superior to the best properties heretofore obtained while ordinary fluctuations were taking place in the stock level.

In other words, it can be demonstrated that maintenance of a stock level at, for example, 11 inches, plus or minus $\frac{1}{4}$ inch, may result in the formation of paper webs having properties that are substantially superior to those properties obtained in webs produced while the stock level averaged 11 inches but fluctuated from perhaps 8 to 14 inches. Also, the properties of webs obtained by holding the level, in accordance with my invention, at perhaps 11 inches, plus or minus $\frac{1}{4}$ inch are far superior to those obtained holding the level at perhaps 10 inches, plus or minus $\frac{1}{4}$ inch. It will thus be

2

appreciated that my invention provides a control means for paper machine operation that was heretofore unappreciated.

5 In addition, the control means which my invention provides are such that production on an ordinary paper machine may be doubled or even tripled without the loss of the improved control which I have just described.

In essence, my invention provides for stock flow wherein the minimum amount of air is entrapped as a result of conducting the stock from one location to another in the machine and the harmful effect of that minimum amount of entrained air is, in turn, minimized by the manner in which the stock flow is accomplished from one location to another, in accordance with the principles of my invention. It will be appreciated that all paper machine stock, being exposed to air as it is at several places in the paper machine, must inherently have some air entrapped therein.

10 In general, my invention embodies four operational features, each of which may, alone, produce a very noticeable effect in the paper machine operation, but two or more of which, in combination, appear to produce even a more unusual improvement, and the optimum operating conditions call for the use of all four of these operational features.

15 The first of these features, is based upon the discovery that one of the principal causes of the formation of lumps in the stock is the action of entrained air in the stock in lateral (non-vertical) reaches of the stock flow conduits. It appears that in lateral reaches of such conduits the entrained air tends to rise to the surface of the stock flowing therethrough and to coat with other bubbles of entrained air rising to the top to form, presumably first a foam-like material, and subsequently a slime, whereby 20 impurities, fibers, and the like are collected at the tops of such conduits. I have found that the collection of this slime or sludge (which frees itself in the form of particles or lumps which interfere with uniform operation) may be substantially avoided by constructing all lateral reaches of the stock conduits so that the roof portions thereof are inclined upwardly at a slope sufficient to permit or cause entrained air to move forwardly and upwardly with the flowing stock. I have found that the slope of such incline is preferably at least 1 inch per linear foot and most preferably at least about $1\frac{1}{2}$ inches per foot, in the direction of stock flow, as I disclosed in my copending application Serial Number 215,543, filed March 14, 1951, and now abandoned, of which this is a continuation-in-part.

25 In general, paper machines are designed so that the maximum production rate is approximately three times the minimum contemplated production rate. As a rule, minimum flow rates of not less than approximately $1\frac{1}{2}$ feet per second are contemplated in such designs, so that the flow rate will be sufficient to maintain the stock fibers in suspension, but the maximum flow rates may be substantially greater than this figure. As another feature 30 of my invention, I have found that if flow rates of 9 feet per second or more are used in one or more stock conduits, it is not necessary to incline the horizontal reaches of such conduits so as to avoid the formation of lump-forming sludge deposits on the roof portions of the conduits. In other words, I find that it is necessary to raise stock streams flowing at $1\frac{1}{2}$ —9 feet per second, 35 so that the tops of such streams are raised at a rate of at least about one inch per linear foot in order to avoid sludge formations along the conduit roofs; but, in the event that conduits may not be conveniently provided for effectively raising the tops of stock streams, as described, 40 then it is necessary to induce stock flow in such conduits at rates of 9 feet per second or more. As will be appreciated, 45

ciated, flow rates of 9 feet per second at various parts in a paper machine may be handled easily, but in certain other parts of the paper machine, a flow rate of 9 feet per second is out of the question.

A second particularly important feature of my invention resides in the avoidance of waterfalls in the white water system. Heretofore, the practice in collecting white water in the wire pit has been to permit the water collected in the save-alls to fall freely down the save-all spouts into the wire pit and the water collected in the seal pit is pumped into conduits which permit the free fall of water into the wire pit. I have found that this customary, and rather obvious, way of collecting white water in the wire pit has the extremely undesirable effect of gathering or entrapping an excessive amount of air, which greatly accelerates the formation of slime in those portions of the stock conduits, such as the horizontal reaches, which are peculiarly adapted for the collection of slime. As I have mentioned, the amount of air ordinarily entrapped in the white water during the dumping of the same into the wire pit from the save-alls or the seal pit has been heretofore disregarded, or at least assumed to be so negligible that it could not possibly produce an undesirable effect in the operation of the paper machine. I have found that this is not the case, and that numerous defective features of paper machine operation may be attributed to this so-called hidden amount of entrapped air.

In accordance with my invention, no "waterfalls" are employed in transferring stock from one pool or pond to another, such as the transfer of stock from the save-alls or the seal pit to the wire pit. Instead, I provide for fluid communication between, for example, the save-all and the wire pit so that a "water leg" may be maintained between the two and levels of liquid maintained in each. I use the term "water leg" in contradistinction to the concept of free falling liquid or a waterfall, in that a water leg is a solid continuous enclosed fluid body which communicates with two different larger fluid bodies or ponds of stock. I use the term "pond" herein to designate generically all such bodies or ponds in a paper machine, as contrasted to the specific use of the stock pond in the head box.

Also, I use the term "stock" herein to mean rich stock as well as the extremely dilute stock, generally referred to as white water in the paper machine art. For example, the stock in the stuff box or stock box may have a concentration of about 3½%, the stock entering the head box may have a concentration of approximately 0.25%, and the stock generally designated as "white water" may have a concentration of only a small fraction of a percent. In general, I have found the behavior of stocks having the aforementioned different concentrations to be approximately the same for the purposes of my invention.

A third feature of my invention is based upon the discovery that it is possible to remove, or permit the escape of a very substantial amount of entrapped air in the white water in the wire pit by increasing the necessary flow of white water therein to at least a distance greater than the length of the wire pit. Heretofore, the seal pit for the suction box drop legs and the save-all inlets to the water pit dumped the white water therein and it flowed directly down into the wire pit discharge. I have found that it is of appreciable importance in effecting the removal of a maximum amount of air from the stock, even though that air is substantially below what was heretofore thought to be the maximum amount of harm-producing entrained air. I have found that by lengthening the travel of the white water in the wire pit, it is possible to remove this additional amount of entrained air.

As a fourth important feature of my invention, I have found that a very substantial amount of harmful air has been caused to enter the stock flow system by the stuff

box operation heretofore used. Heretofore, it was the common practice to feed stock from the stuff box into the system through a weir or some other type of measuring device which necessarily involved a waterfall. I have found that such a waterfall results in the collection of a very substantial amount of harmful entrapped air in the stock. Accordingly, I provide a stuff box arrangement wherein a stock or water leg is provided between the fixed level in the stuff box and the inlet to the fan pump.

It is, therefore, an important object of my invention to provide an improved stock flow method and apparatus whereby the entrapment of air in the stock is minimized and the harmful effect of entrapped air in the stock is also minimized.

It is a further object of my invention to provide a method of conducting stock via a water leg from one pond to another in a paper machine, that comprises drawing a stream of stock from below the level of one pond to below the level of the other, confining such stream in a closed system between said ponds, and raising the stream top at a rate at least sufficient to prevent air accumulation therat during all lateral stream travel.

It is another object of my invention to provide an improved method of conducting a stream of stock through a given amount of lateral travel to a pond in a paper machine, that comprises flowing the stream in a pipe at a minimum linear velocity of 1½ feet per second and raising the top of all laterally directed stock stream portions not flowing at at least 9 feet per second at a rate of at least one inch per foot, and preferably 1½ inches per foot, in the direction of travel.

It is yet a further object of my invention to provide an improved method of and apparatus for operating a white water system in a paper machine, in accordance with the principles described herein.

It is yet another object of my invention to provide an improved method of and apparatus for operating a paper machine stuff box, in accordance with the principles described herein.

It is still a further object of my invention to provide, in a paper machine, a chamber for retaining a stock pond, a conduit communicating with said chamber for conducting stock flow vertically and laterally, and flow control means in said conduit for maintaining a stock pond in said chamber of predetermined level above the communicating conduit, all the lateral reaches of said conduit having roof portions inclined upwardly in the direction of stock flow at a slope of at least one inch per foot.

It is still another object of my invention to provide an improved method of an apparatus for operating a paper machine wherein the piping is arranged to avoid waterfalls and to avoid the collection of slime along the tops of horizontal reaches of conduits.

Other important objects, features, and advantages will become apparent to those skilled in the art from the following description and drawings of preferred embodiments of my invention.

On the drawings:

Figure 1 is a side elevational view of a paper machine embodying my invention, with parts shown diagrammatically, in section, and fragmentarily;

Figure 2 is a top plan view taken substantially along the lines II—II of Figure 1;

Figure 3 is an elevational sectional view taken substantially along the lines III—III of Figure 2;

Figure 4 is a sectional elevational view taken substantially along the lines IV—IV of Figure 1;

Figure 5 is an end elevational view taken from the right hand side of Figure 1 and 2, showing the head box piping arrangement embodying my invention;

Figure 6 is a top plan view showing a modified fan pump piping system embodying my invention; and

Figure 7 is a sectional elevational view taken substantially along the lines VII—VII of Figure 6.

As shown on the drawings:

In Figure 1, the reference numeral 10 refers generally to a paper machine having a piping arrangement for stock flow embodying my invention. In the paper machine 10 the stock flows from a head box 11 onto the forming wire W which is trained about a breast roll 12 at the head box and a couch roll 13 at the opposite end. For the sake of clarity, many details of the paper machine structure, such as the various guide rolls and turning rolls for the wire W, have been omitted from the drawings, since their particular arrangement is not a part of the instant invention and such arrangements are well known to those skilled in the art.

Considering first the flow of white water through the save-all system, as is well known in the art, at the breast roll end of the wire W water passes rapidly out of the stock through the wire W and falls into the save-alls, designated by the reference numeral 14 generally and shown only diagrammatically in Figure 1. In general, the save-alls 14 comprise open topped tray-like conduits which catch the water falling through the wire W and are slanted slightly so as to divert the water to the downspouts 15 and communicate with the wire pit 16 via laterally extending conduit portions 17 entering the side wall 16a of the wire pit 16 and having roof portions or tops 18 which are inclined upwardly in the direction of stock flow; that is, the roof 18 is inclined upwardly from the point at which the conduit 17 communicates with the vertical portion of the downspout 15 to the point at which the conduit 17 communicates with the wire pit side wall 16a.

The upward slope of the room 18 is at least that sufficient to prevent appreciable accumulation of air at the top of the stock or white water stream flowing through the conduit 17, which slope has been found to be at least about 1 inch per foot and preferably at least about 1½ inches per foot. The floor of the conduit 17 may be substantially level and aligned with the wire pit floor adjacent thereto, as shown herein, but the top of this "horizontal reach" or lateral duct work 17 must, in accordance with the invention, be upwardly inclined or the accumulation of air bubbles, foam, etc. will ultimately built up slime and sludge on the roof 18. The sludge tends to break loose in chunks during operation so as to cause numerous operational difficulties, as will be appreciated by those skilled in the art.

I also provide valve means 19 in each downspout 15 below the level L-1 of the white water in the wire pit 16. Preferably these valve means 19 are a damper type valve adapted to effect a substantial pressure drop in the stream of white water by restricting the flow thereof. The valves 19 are adapted to restrict the stream flow to the extent necessary to maintain constantly a level L-2 in the save-all 14, which involves developing a pressure drop across the valve 19 equal to the head of water equivalent to the difference between the wire pit level L-1 and the save-all level L-2. Also, the save-all 14 and downspout 15 structure is arranged so that the downward stock flow, taken with respect to the save-all level L-2 (or the top of the white water pond in the save-all 14) is preferably not more than about 1 foot per second, and most preferably not more than about 0.5 foot per second, so that a whirlpool or vortex will not be formed to draw air into the stock.

The valves 19 may, of course, be controlled manually so as to maintain the necessary pressure drop thereacross, or they may be controlled automatically by suitable control means responsive to the save-all level L-2. For example, a float actuated control means, designated generally by the reference numeral 20, and shown diagrammatically, in Figure 4 may be used to control the actuation of the valve 19, so as to maintain a predetermined level L-2 in the save-all. As will be appreciated, the valves 19 are positioned below the level L-1 of the wire pit 16,

so that there is no tendency to draw a vacuum in the downspout 15 during actuation of the valve 19.

It will thus be seen that, in general, the arrangement for conducting white water from the save-all 14 to the wire pit 16 is one wherein there are no free "water-falls" and a dynamic, as contrasted to a static, water leg is maintained between the pond of white water in the save-all 14 and the pond of white water in the wire pit 16, via the downspout 15 and valve 19 arrangement. In addition, the piping arrangement is such that substantially all of the lateral or horizontal reaches in the piping arrangement have upwardly inclined roof portions, as described, and substantially all of the downwardly directed reaches of such piping are directed downwardly in a vertical direction. I use "substantially" advisably, since it is apparent that the small portion of the piping designated by the reference numeral 15a does not conform with the general rules for piping arrangements of the invention. This small section 15a has been illustrated herein for the purpose of showing that suitable operating conditions may be obtained, even though a very small section of a horizontal reach does not have an inclined roof or a very small section of a downwardly directed conduit is not vertical. As will be appreciated, there may be certain piping arrangements which cannot be avoided or which can be avoided only by extremely impractical means. If one or two of such "defective" piping features is employed the advantages of my invention may still be realized, since the net effects of such defects in an extremely minute portion of the overall piping may be insignificant. However, it is by far more advantageous to carefully avoid all, or at least all significant defects of this type in the practice of my invention, since I have found that only a single defective point may be a source of very great trouble. The advantages of my invention include greatly improved flow control so that the particular head box level which gives optimum results may be maintained continuously. As will be appreciated, only a single slug of air or chunk of sludge developed at such a defective point and passing through the fan pump may result in an appreciable disturbance of this level, and only occasional disturbances of this nature may quite easily render the entire control ineffective.

Also, it should be mentioned that the presence of the defective piping at 15a, as I have chosen to illustrate it, is at a point most remote from the fan pump, thereby rendering this defect least harmful in nature. The defective piping at 15a should, however, in the most preferred embodiment of my invention, be altered so as to comply with the general piping arrangement structure of the invention; for example, by extending the save-all sides so that a straight vertical draw from the save-all bottom could be arranged.

As still another aspect of my invention, I desire to refer to the structure 21 in Figure 4 showing, at the position opposite location 15a, an upwardly inclined roof terminating with a bleed-off valve and merging with a vertical downward reach. In such a structure the "slope" of the top of the stock stream changes abruptly from plus to minus. I have tested such structures in paper machines and I have found that there is a very great tendency for slime to collect upon the conduit roof whereat the stream slope changes from more than zero to minus one (vertically downward); but that formation of slime thereat may be avoided merely by maintaining a substantially constant air bleed at the point. There are, of course, certain practical limits to the number and extent of such installations in a paper machine, but such an arrangement may be found to be more practical than extensive re-arrangement of the piping. It will thus be seen that all downward piping should not only be vertical but should also be positioned directly under bodies of stock having their tops exposed to air for venting purposes, and should provide direct communication vertically from such piping to an air-exposed top surface of a stock body or pond.

The white water falling through the wire W and into the save-all 14 , in passing through the air and in splashing in the save-all 14 , picks up or entraps an appreciable amount of air. In the instant invention, additional air pick up is prevented from this point on by the elimination of additional waterfalls in the paper machine stock flow. Also, the instant invention provides for the release of substantial amounts of the air thus entrapped and the elimination of substantial amounts of the foam or froth which may result from the splashing in the save-alls, for example.

As is best seen in Figure 2, the wire pit 16 receives the white water from the vertical downspouts 15 and the lateral conduit portions 17 in side channels 22 and 23 , which are separated from a central longitudinally extending channel 24 by means of longitudinally extending walls 25 and 26 respectively. The floors $22a$ and $23a$ of channels 22 and 23 , respectively, slope gently in a forward longitudinal direction with respect to the paper machine to direct the white water flow forward as shown by the arrows. At the forward end of the channels 22 and 23 there are provided apertures $25a$ and $26a$ in the walls 25 and 26 , respectively, for fluid communication between the central channel 24 and each of the side channels 22 and 23 .

The various walls of the wire pit 16 and the other structural portions of the wire pit 16 are formed of grout or mortar, as is the usual practice in paper machine construction. As is best seen in Figure 1, each of the apertures $25a$ and $26a$ in the grout walls 25 and 26 , respectively, is flush with the channel floors $22a$ and $23a$ respectively and is submerged substantially below the level $L-1$ in the wire pit 16 . The portions of the walls 25 and 26 extending upwardly over the apertures $25a$ and $26a$, respectively, extend above the level $L-1$, and overflow gates 27 and 28 in the wire pit forward end wall $16b$ effectively maintain the level $L-1$ below the tops of the walls 25 and 26 and also effectively remove foam or the like floating material on the white water surface. Such material spilling over the top of the gates 27 and 28 may be dumped in the sewer, or reprocessed, if desired.

In the channel 24 , whose floor $24a$ slopes gently backward in reverse to the slope direction of the floors $22a$ and $23a$, the white water flows rearwardly of the machine 10 and into a lower basin 29 . During the entire travel of the white water from its entrance into the wire pit 16 from the conduit 17 up to and including its flowing into the basin 29 , the white water top surface is uncovered to permit maximum release of entrapped air. Heretofore the practice was to permit white water to fall into the water pit and then flow through the shortest possible path directly to the lowermost discharge portion of the wire pit, which would correspond to the basin 29 in the instant structure. In the instant structure, however, the walls 25 and 26 are so arranged that the middle channel 24 is substantially the longitudinal dimension of the wire pit in length and an appreciable amount of flow (even from the nearest inlet conduits 17) must take place in the side channels 22 and 23 before the white water enters the channel 24 . All white water must flow at least the longitudinal dimension of the wire pit 16 before being discharged therefrom, and preferably a distance appreciably more than the longitudinal dimension of the wire pit 16 . As will be appreciated, the maximum travel path in the wire pit depends upon the member of walls such as the walls 25 and 26 which may be installed, as a practical matter, in a wire pit to accommodate suitable paper machine operation. In the instant structure, about twice the longitudinal dimension of the wire pit 16 is the maximum travel path for the white water, and it has been found that, in most instances, this is a sufficiently long travel path, although three or four times the longitudinal dimension of the wire pit may also be found to be a suitable travel path.

In an arrangement such as the instant wire pit arrange-

ment, wherein the stock travel path averages about $1\frac{1}{2}$ to 2 times the longitudinal dimension of the wire pit, it is preferable to so design the wire pit that the necessary amount of white water may pass therethrough, and the rate at which the stock flows laterally (or longitudinally) in the wire pit should not be substantially in excess of $1\frac{1}{2}$ feet per second. Preferably the white water flow rate is about $\frac{1}{2}$ to $1\frac{1}{2}$ feet per second in the wire pit 16 . If the flow rate in the wire pit 16 is too rapid, the turbulence of the white water at the top surface thereof may cause additional entrapment of air. As previously mentioned, the minimum flow rate of strong or concentrated stock in pipes is about $1\frac{1}{2}$ feet per second, in order to be certain of maintaining a uniform fiber suspension therein; but white water is such a dilute "stock" that it need not be caused to flow quite as fast. As will also be appreciated, the flow rate in open topped conduits such as the wire pit and the save-all is maintained for the purpose of permitting the release of entrapped air and there is no problem of slime formation along the roof of the conduit.

As is best shown in Figure 4, the white water flows from the basin 29 through a lateral discharge opening 30 , through a laterally extending grout conduit 31 and into the intake chamber 32 to the fan pump (not shown). The floor 34 of the laterally extending conduit 31 is sloped gently downwardly, but the roof 35 of the laterally extending conduit 31 is inclined upwardly in substantially the same manner that the roof 18 of the laterally extending conduit portion 17 is inclined upwardly. It will thus be seen that the roof portion 35 of the entire lateral reach here involved is inclined upwardly in the manner and for the purposes hereinbefore disclosed in detail. Also, the conduit 31 is arranged to provide a continuous water leg from below the level $L-1$ in the wire pit 16 to below the level $L-4$ in the fan pump intake chamber 32 . Actually, the level $L-1$ and the level $L-4$ are substantially the same. There is a slight drop in the white water level as it passes from the side chambers 22 and 23 to the middle chamber 24 in the wire pit 16 , and there is another slight drop as the white water passes from the middle chamber 24 to the fan pump intake chamber 32 , when the white water is flowing in normal operation of the paper machine 10 .

Referring now to the arrangement involving the seal pit 36 , which is shown fragmentarily and diagrammatically in Figures 1, 2 and 3, in the paper machine 10 underneath the wire W near the couch roll 13 there are provided a plurality of flat boxes or suction boxes 37 which closely underlie the wire W and operate to de-water the web thereon by the application of suction forces to the bottom of the wire W . Each flat box 37 is provided with one or more drop legs 38 through which a vacuum is pulled in the flat boxes 37 and which extends downwardly a substantial distance to the seal pit 36 .

As is shown best in Figure 3, each drop leg 38 extends into the seal pit 36 so that its lower extremity is submerged a substantial distance below the white water level $L-5$ that is maintained in a central longitudinally extending chamber 39 , defined by a pair of longitudinally extending walls 40 and 41 , the seal pit back wall $36a$ (Figure 2) and a laterally extending partition wall 42 (Figure 2). As will be appreciated, the reduced pressure in the drop leg 38 causes a white water level to be maintained therein that is substantially higher than the level $L-5$ in the middle chamber 39 .

The four outside walls $36a$, $36b$, $36c$ and $36d$ of the seal pit 36 , and the inner walls 40 and 42 all extend to substantially the same height. The remaining inner wall 41 does not extend upwardly as far and its top has a knife edge structure 43 which slants away from and down from the inner chamber 39 , so that white water overflowing at the level $L-5$ from the inner chamber 39 to an outer chamber 44 may flow downwardly to the slightly lower level $L-6$, which is the white water level for the

remainder of the seal pit 36. The knife edge arrangement 43 minimizes the waterfall effect obtained by flowing water over the top of the wall 41. Although a submerged discharge for the inner chamber 39 would be preferable in avoiding completely any waterfall effect, certain operational difficulties would be involved because of the reduced pressure in the drop legs 38. In general, it is preferable to employ a seal pit arrangement whereby there is no possibility that the seal pit might be pumped dry so as to expose the bottom of the drop leg 38. Instead, I have found that suitable operation may be obtained employing the two chambers 39 and 44 with a submerged discharge aperture 45 for the second chamber 44.

In the seal pit 36, the white water thus flows from the middle chamber 39 over the wall 41 into the second chamber 44, through the submerged discharge opening 45 and into the third chamber 46, whence the white water flows the full length of the seal pit 36 (like the flow in the wire pit 16) and into the seal pit pump suction or intake line 47 (as best shown in Figure 2). From the seal pit pump 48 the white water is pumped rearwardly of the paper machine 10 through a first lateral reach of piping 49, then through a second lateral reach of piping 50 which extends laterally beneath the wire pit 16, next through a third lateral reach of piping 51 which extends along the side of the wire pit and to the rear thereof, and finally to a fourth lateral reach of piping 52, which serves as a header for three laterally extending inlet pipes 53. The inlet pipes 53 extend through the rear end wall 16c of the wire pit 16 at spaced intervals so as to permit a relatively uniform distribution of the seal pit white water flow entering at the back end of the wire pit 16. The white water flows therefrom in substantially the same manner as that described for the flow of white water from the save-alls, once it has entered the wire pit 16.

As can be seen from Figures 1 and 2 all of the lateral reaches of piping 49, 50, 51, 52 and 53 are upwardly inclined in the direction of flow, the rate of incline being that described hereinbefore in connection with the roof portions of the conduit.

The first lateral reach of seal pit piping 49 is provided with a control valve 54, which control the rate of discharge from the seal pit pump 48, so as to maintain the desired level L-6 in the seal pit. Preferably, automatic control means, diagrammatically indicated at 55, which are responsive to the level L-6 are provided for automatic control of the valve 54. In the operation of the seal pit pump, it will be appreciated that white water is withdrawn from the seal pit 36 from below the level L-6 therein and is piped upwardly to the wire pit 16, below the level L-1 therein, so that again there is a water leg maintained between the two bodies of white water.

Referring now to the operation of the stuff box 56, as best shown in Figure 1, it will be seen that the stuff box 56 is positioned substantially above the wire W so as to provide for gravity flow of stock from the stuff box 56 to the fan pump intake chamber 32, via the stuff box drop leg 57. In the operation of the stuff box 56 stock is pumped upwardly from the refiners (not shown) through the pipe 58 and into the bottom of the stuff box 56. The stuff box level L-7 is maintained by means of an over flow partition wall 59, which permits the flow of stock thereover and into a bottom discharge pipe 60 which leads to the machine stock chest (not shown). A partition wall 61 positioned between the stock inlet 58 and the drop leg discharge 57 extends upwardly less than the height of the over flow wall 59, so as to be submerged at all times but to increase the travel path of the stock in the stuff box. Preferably control means, as indicated diagrammatically at 62, are provided for operation of a gate in the over flow partition wall 59 so as to give better level control in stuff box 56.

It will thus be seen that as the stock direction of flow

changes from upward direction flowing out of the pipe 58 to downward direction flowing into the pipe 57 the top surface of the stock stream is vented or exposed to the air. The downwardly directed stock stream in the pipe 57 flows substantially vertically from directly below an open topped or vented portion of stock down to a control valve 63, which may be used to control the stock flow, preferably so as to maintain the rate of vertical stock flow from the stuff box at less than 1 foot per second and preferably less than about 0.5 foot per second, for the reasons hereinbefore mentioned. The stock flows through the control valve 63 (below the level L-4) and then through a lateral reach of piping 64, inclined as hereinbefore described upwardly in the direction of flow, which leads into the bottom of the fan pump intake chamber 32. Mixing of the rich stock with the white water thus takes place in the fan pump intake chamber 32, as well as in the fan pump 33.

Communication between the fan pump intake chamber 32 and the fan pump 33 on the suction side is provided by means of a laterally extending conduit 65, which has an upwardly inclined roof portion 66 of the structure hereinbefore described.

As can be seen, the fan pump discharge 33 is connected to a first laterally and upwardly inclined reach of piping 67 which conducts the stock rearwardly a short distance and into a second lateral reach of piping 68, likewise upwardly inclined, which conducts the stock approximately to the longitudinal center line of the paper machine 10 and is connected with a third lateral reach of piping 69 which conducts the stock to a point directly below the head box 11 and into the T-fitting 70.

From the T-fitting 70 the stock stream, split in two substantially equal halves, is directed through the oppositely extending lateral reaches of piping 71, 71, each of which is connected by means of elbows 72, 72 to vertically extending pipes 73, 73. Each of the vertically extending pipes 73, 73 has an elbow 74, and these elbows 74, 74 are connected to the head box on opposite sides thereof near the bottom.

The head box 11 has the same structural arrangement as that described in detail in my copending application Serial No. 215,543, filed March 14, 1951. The box 11 is mounted on spaced supporting posts 75, 75 which rest on the floor F. The bottom rear inlet to the head box 11 is provided with a cross flow stock distributor indicated generally by the reference numeral 76, which comprises a lower distributor casing section 77 defining a pair of open topped cross flow conduits beneath the head box 11, which are co-extensive across the entire width of the head box inlet.

The rear one 78 of the open topped conduits is connected to one of the elbows 74 by means of a conduit 79 and the front one 80 of the open topped conduits is connected with the other elbow 74 by means of a conduit 81. A recirculating line 82 affords communication between the rear open topped conduit 78 and the top portion of the closed conduit 81, for re-circulation purposes; and a pipe 83 in like manner affords communication between the front open topped circuit 80 and the top of the closed conduit 79 for recirculation purposes.

In particular, it will be noted that all of the lateral reaches of the piping from the fan pump 33 to the open top conduits 78 and 80 have the roof portions thereof inclined upwardly in the direction of flow at slopes corresponding to those hereinbefore described in detail. Even the elbows 72 and 74 have the roof portions thereof inclined upwardly to the extent described, so that there will be no horizontal roof portions. Also, the stock flow from the fan pump intake chamber 32 to the head box 11 involves flow from below the intake chamber level L-4 to below the head box level L-3.

Referring now to Figures 6 and 7, which show a modified piping arrangement for the fan pump system, it will be seen that in these figures those elements which func-

tion substantially as the corresponding elements in the previous figures function have been designated by the prime of the same reference numeral. The fan pump 33', in Figures 6 and 7, discharges into a generally arcuate reach of piping which substantially reverses the direction of flow, being generally designated by the reference numeral 84. The piping 84 is connected to a lateral reach of piping 69' which corresponds to the piping 69 shown in Figures 1-5 inclusive, and the piping 84 also has a connection 85 extending substantially horizontally from the fan pump discharge. The connection 85 is, in turn, connected to a generally L-shaped horizontal reach of piping for reversing the direction of stock flow therein, generally designated by the reference numeral 86 (Figure 6). The L-shaped section 86 has a control valve 87 therein, which may be used to control the stock flow from the fan pump 33' through the connection 85 and the piping 86.

At the bottom of the stuff box drop leg 57' below the control valve 63', there is an elbow 88. The end of the piping 86 not connected at 85 communicates with the elbow 88, via a welded joint in the curve portion of the elbow. It will thus be seen that mixing between the rich stock from the stuff box and the stock diluted to the desired concentration for use in the head box may take place in the elbow 88 and the horizontal reach of piping 89 connected thereto.

The horizontal reach of piping 89 is connected to a downwardly sloped reach of piping 90 which directs the stock flow to an upwardly sloped inlet pipe 91 for the fan pump intake chamber 32', so that the enriched stock may be mixed with the white water in the intake chamber 32'.

As will be appreciated, the intake chamber 32' in the piping arrangement shown in Figures 6 and 7 is in effect a downward extension to the basin 29 shown in Figures 1, 2 and 4. The advantages of the structure shown in Figures 6 and 7 include the relatively short stock travel from the fan pump to the head box and a preliminary admixing of stock at the elbow 88.

As will be appreciated also, the piping 85, 86, 89 and 90 is not arranged so as to conform with the structure hereinbefore described, in that the downwardly extending pipe 90 is not vertical and the lateral reaches 85, 87 and 89 are not upwardly inclined. In this particular structure, however, it is necessary to pump the stock through the piping 85, 86, 89 and 90 at rates of 9 feet per second or more, since as was mentioned hereinbefore flow rates of 9 feet per second or more have been found to be sufficiently rapid to prevent the harmful effects resulting from air accumulation at the top of horizontally flowing streams of stock. Apparently, the turbulence in stock streams flowing at rates of at least 9 feet per second is such that no appreciable separation of air may take place. It so happens that flow rates of 9 feet per second may be maintained at various machine operating speeds in the particular recirculating piping arrangement of Figures 6 and 7, in the piping sections 85, 86, 89 and 90, although flow rates of 9 feet per second or more may not be used in other portions of the piping.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A method of operating a white water system in a paper machine having white water save-all and wire pit levels maintained therein so as to minimize the harmful effects of entrapped air in the white water and to have optimum flow control conditions, that comprises piping white water downwardly and laterally from below a save-all level to below the wire pit level through a water leg maintained by restricting the flow therein at a

point below the wire pit level so as to maintain constantly a save-all level, piping white water upwardly and laterally from below the seal pit level to below the wire pit level through a water leg maintained by restricting the flow from the seal pit to maintain a seal pit level, and piping white water laterally from the wire pit discharge below the wire pit level at a rate to maintain a substantially constant wire pit level, the white water streams thus piped laterally being raised at their tops at a rate of at least 1 inch per foot of travel above the horizontal in the direction of travel.

2. A method of operating a white water system in a paper machine having white water save-all and wire pit levels maintained therein so as to minimize the harmful effects of entrapped air in the white water and to have optimum flow control conditions, that comprises piping white water downwardly and laterally from below a save-all level to below the wire pit level through a water leg maintained by restricting the flow therein at a point below the wire pit level so as to maintain a constant save-all level, piping white water upwardly and laterally from below the seal pit level to below the wire pit level through a water leg maintained by restricting the flow from the seal pit to maintain a seal pit level, and piping white water laterally from the wire pit discharge below the wire pit level at a rate to maintain a substantially constant wire pit level, the white water streams thus piped laterally being raised at their tops at a rate of at least 1 inch per foot of travel above the horizontal in the direction of travel, and the water piped from the save-alls and the seal pit being caused to flow in the wire pit at a rate of $\frac{1}{2}$ to $1\frac{1}{2}$ feet per second for a distance of at least the longitudinal dimensions of the wire pit before being discharged therefrom, and the rate of discharge from the pit being maintained at less than a downward velocity of 1 foot per second.

3. In a paper machine, a white water system comprising a seal pit for receiving water from the flat box drop legs and adapted to maintain a water level therein, a wire pit also adapted to maintain a water level therein and positioned above said seal pit, a conduit having vertical and lateral reaches and affording fluid communication between below the water level of said seal pit and below the water level of said wire pit, and pump means in said conduit to effectively retain a level in said seal pit and said wire pit and a water leg between the water levels in said seal pit and said wire pit, all the lateral reaches of said conduit having roof portions inclined upwardly in the direction of stock flow at a slope of at least 1 inch per foot.

4. In a paper machine, a white water system comprising a save-all adapted to maintain a water level therein, a wire pit also adapted to maintain a water level therein and positioned below said save-all, a downspout affording fluid communication through downwardly and laterally extending reaches between the bottom of said save-all and below the water level in said wire pit, let-down valve means in said downspout below the wire pit level to effectively retain a level in said save-all and a water leg between the water levels in said save-all and said wire pit, a seal pit adapted to receive water from flat box drop legs and to maintain a water level therein, said seal pit being positioned downwardly and laterally from said wire pit, a conduit having vertical and lateral reaches and affording fluid communication between below the level in said seal pit and below the level in said wire pit, and pump means in said conduit to effectively retain a level in said seal pit and a water leg between the water levels in said seal pit and said wire pit, all the lateral reaches of said downspout and said conduit having roof portions inclined upwardly at a slope of at least 1 inch per foot.

5. In a paper machine, a white water system comprising a save-all adapted to maintain a water level therein, a wire pit also adapted to maintain a water level therein and positioned below said save-all, a downspout affording fluid communication downwardly and laterally be-

tween the bottom of said save-all and below the water level in said wire pit, let-down valve means in said downspout below the water pit level to effectively retain a level in said save-all and a water leg between the water levels in said save-all and said wire pit, a seal pit adapted to receive water from the flat box drop legs and to maintain a water level therein, said seal pit being positioned downwardly and laterally from said wire pit, a conduit affording fluid communication between below the level in said seal pit and below the level in said wire pit, pump means in said conduit to effectively retain a level in said seal pit and a water leg between the water levels in said seal pit and said wire pit, said downspout and said conduit having lateral reaches and all the lateral reaches of said downspout and said conduit having roof portions inclined upwardly at a slope of at least 1 inch per foot, a stuff box adapted to maintain a stock level therein, an inlet conduit communicating with said stuff box below the stock level and adapted to supply stock to maintain the stuff box level, an outlet conduit communicating with said stuff box below the level, a fan pump having its intake in communication with the other end of said discharge conduit, and a let-down valve in said discharge conduit positioned at a height below the effective water head at said fan pump intake and adapted to effectively retain a stock level in said stuff box and a stock leg between said stuff box and said fan pump intake.

6. In a paper machine, a white water system comprising a save-all adapted to maintain a water level therein, a wire pit also adapted to maintain a water level therein and positioned below said save-all, a downspout affording fluid communication downwardly and laterally between the bottom of said save-all and below the water level in said wire pit, let-down valve means in said downspout below the water pit level to effectively retain a level in said save-all and a water leg between the water levels in said save-all and said wire pit, a seal pit adapted to receive water from the flat box drop legs and to maintain a water level therein, said seal pit being positioned downwardly and laterally from said wire pit, a conduit affording fluid communication between below the level in said seal pit and below the level in said wire pit, pump means in said conduit to effectively retain a level in said seal pit and a water leg between the water levels in said seal pit and said wire pit, said downspout and said conduit having lateral reaches all the lateral reaches of said downspout and said conduit having roof portions inclined upwardly at a slope of at least 1 inch per foot, a stuff box adapted to maintain a stock level therein, an inlet conduit communicating with said stuff box below the stock level and adapted to supply stock to maintain the stuff box level, an outlet conduit communicating with said stuff box below the level, a fan pump having its intake in communication with the other end of said discharge conduit, and a let-down valve in said discharge conduit positioned at a height below the effective water head at said fan pump intake and adapted to effectively retain a stock level in said stuff box and a stock leg between said stuff box and said fan intake, a head box, a third conduit affording fluid communication between said fan pump discharge and the bottom of said head box, all the lateral reaches of said downspout, said first, said second, and said third conduits having roof portions inclined upwardly at a slope of at least 1 inch per foot.

7. In a paper making machine having a stock inlet, a looped web forming wire having an upper run receiving stock from the inlet, suction means acting through the upper run of the wire to dewater a web on the wire, drop legs draining said suction means, a seal pit receiving said legs, a save-all pan underlying said upper run of the forming wire, a wire pit beneath said pan, a stock box having a drop leg feed pipe, a stock pump having an inlet and an outlet, the improvements of conduit means containing vertical and non-vertical portions connecting the seal pit with the wire pit, the save-all pan with the wire pit, the

75

drop leg feed pipe with the pump inlet and the pump outlet with the stock inlet, said conduit means having all non-vertical portions provided with roofs which are inclined upwardly at least one inch per foot of length and said wire pit having an elongated open top flow path for fluid from the seal pit and the save-all pan of greater length than the length of the wire pit and discharging into the stock pump inlet.

8. A paper machine cross-flow stock distributor comprising a pair of open-topped flow conduits adapted to receive oppositely flowing stock streams therein, means establishing stock flow from said conduits through the open tops thereof to a paper machine inlet box, and stock flow passages having lateral reaches for introducing stock flow into said conduits, all lateral reaches of said passages having roof portions which are inclined upwardly along the direction of travel of stock therethrough for preventing the separation of entrained air from stock flowing through said passages.

10 9. In a paper machine cross-flow stock distributor having a pair of open-topped flow conduits adapted to receive oppositely flowing stock streams therein for introduction into the stock inlet box through the open tops of the conduits, the improvements which comprises stock flow passages having horizontal reaches through which stock is introduced into said conduits and stock recirculation passages also having horizontal reaches establishing communication between said conduits, all the horizontal reaches of said passages having roof portions inclined upwardly along the direction of stock flow therethrough for preventing the lumping of stock flowing through said passages and into said conduits.

15 10. A paper machine cross-flow stock distributor comprising a pair of open-topped flow conduits adapted to receive oppositely flowing stock streams therein for discharge into a stock inlet box, stock recirculatory passages having lateral reaches and establishing communication between said conduits adjacent the ends thereof, stock flow passages having lateral reaches and communicating with said conduits, and stock flow passage elbows for establishing stock flow from a source to said passages, all the lateral reaches of said recirculatory passages and said stock flow passages having roof portions inclined upwardly along the path of stock flow travel therethrough at a slope of at least one inch per linear foot, and said stock flow elbows having eccentric upper and lower curved surfaces to provide an effective upward slope of the elbow passage roof.

11. A paper machine cross-flow stock distributor comprising a pair of open-topped flow conduits adapted to receive oppositely flowing stock streams therein for discharge into a stock inlet box, means establishing stock flow into opposite ends of said conduits, and means establishing communication between said conduits adjacent the other ends thereof for the recirculation of stock between said conduits, said last-mentioned means including stock conduits of reduced size and joining elbows having lateral reaches and having roof portions inclined upwardly along the path of travel of stock in all lateral reaches thereof for preventing segregation of air entrained in the stock and air collection in the stock passages and elbows as a consequence of stock flow therethrough.
